FABRICATED METAL ARTICLE AND METHOD
OF MAKING SAMEJames W. Hughes, Detroit, Mich., assignor to
Chrysler Corporation, Detroit, Mich., a corpo-
ration of Delaware

Application May 3, 1933, Serial No. 669,088

3 Claims. (Cl. 74—588)

This invention relates to improved fabricated metal articles and to the method of making the same.

More specifically, my invention relates to the manufacture of improved fabricated levers and connecting rods for operatively connecting parts of a mechanism together.

The main objects of the invention are to provide improved articles of the above character which have relatively high structural strength per unit of weight; to provide improved operative connecting devices which have body portions formed mainly of ordinary ferrous metal wire elements; to provide die cast portions having sockets for receiving the ends of such wire elements; to provide alloy films between the interior surfaces of such sockets and the registering outer surfaces of the wire received therein which are integrally united with such surfaces; and to provide convenient parts in a structure of this character which are particularly adapted to be simultaneously welded together by a copper-hydrogen welding process.

Other objects of the invention are to provide an improved method of fabricating devices of this kind, such as levers and connecting rods, by means of which both plate and wire stock can be used without substantial cross-sectional change from the form in which it is received from the mills; to provide a method of this kind in which a plurality of parts may be temporarily assembled in their final relation and simultaneously welded together; and to provide a method for fabricating ferrous metal parts into a substantially finished product which eliminates practically all trimming of welding metals and alloys from the joints of such parts.

An illustrative embodiment of the invention is shown in the accompanying drawing, in which: Fig. 1 is a vertical cross-sectional view schematically illustrating a furnace in which the parts of my improved fabricated articles may be conveniently simultaneously welded together.

Fig. 2 is a side elevational view of the connecting rod of the type used in internal combustion engines showing the parts in a temporary secured together relation.

Fig. 3 is a transverse sectional view taken on the line III—III of Fig. 2.

Fig. 4 is a side elevational view of a bearing cap for the connecting rod.

Fig. 5 is an end elevation of the bearing cap shown in Fig. 4.

Fig. 6 is a side elevational view of a link type operative connecting device illustrating a further development of the invention and showing the parts thereof in a temporarily secured together relation.

Fig. 7 is a plan view of the device illustrated

in Fig. 6 showing parts thereof removed to disclose the underlying structure.

In Figs. 2 to 5, inclusive, my invention is illustrated as it applies to the construction of an internal combustion engine connecting rod. The connecting rod comprises a wrist pin bearing portion 10, preferably die forged ferrous metal, having a pair of adjacent sockets 11 in one side into which ferrous metal wire elements 12 extend. The intermediate portions of the wire elements 12 diverge outwardly with respect to each other and the end portions thereof are offset outwardly and they terminate in substantially straight threaded sections 13. The outwardly offset end portions of the wire elements 12 provide a yoke-shaped structure in which is received a journaled portion 14 including a semi-cylindrical collar 15 that is provided throughout the outer portions of its periphery with grooves or depressions 16 for receiving the offset end portions of the wire elements. Formed in the extremities of the semi-cylindrical collar 15 are rectangular-shaped recesses 17 in which blocks 18, preferably comprising ferrous metal, are mounted. The blocks 18 constitute ears or flanges and are provided with apertures 19 for receiving the straight sections of the end portions of the wire elements 12.

Mounted between the wire elements 12 is a web structure including a substantially triangular-shaped plate 20 having its longitudinal edges seated in recesses 21 formed in the adjacent sides of the wire elements 12. The web has a reinforcing flange 22 mounted upon and disposed at substantially 90° to the plate 20. The flange 22 is provided with tongues 23 which are received in apertures formed in the central portion of the plate 20. The left extremities of the plate 20 and flange 22 are seated in recesses 24 formed in the journal portion 10 and the right extremities of these members are seated in recesses 25 provided in the outer periphery of the central portions of the collar 15.

Prior to assembling of the above described parts in the relation illustrated, their surfaces are coated with a film of copper or alloy including copper and such coating is applied to the surfaces of all of the above mentioned grooves, depressions, recesses and tongues of the respective parts. The parts are assembled in the relation desired in the finished product and they are temporarily secured together, particularly at the crankshaft end of the connecting rod by a clamping block 25, preferably comprising chrome steel, which is provided with apertures for receiving the straight end sections of the wire elements 12. The block 25 is urged against the end of the journal portion 14 by bolts 26 threaded on the ends 13 of the wire elements. These bolts firmly draw the offset portions of the wire elements, collar 15 and blocks 18 into close-fitting relationship.

A slight binding fit between the left ends of the wire elements 12 and the sockets 11 in which they are received is relied upon to temporarily secure the parts at the left end of the connecting rod 5 together.

After the parts are temporarily secured together they are placed upon an endless belt 27, preferably formed of heat resisting metal, by which they are carried through in a muffle 28 of a furnace 29. 10 The muffle 28 is surrounded by a chamber 30 which is heated in any suitable manner such as, for example, by a gas burner 31. The conveyor 27 moves the article from the left to the right end of the muffle and an inlet pipe 32 is provided at the right 15 end of the muffle for supplying hydrogen to the interior of the muffle which preferably flows, in a direction opposite to the travel of the articles, to the left end of the muffle where it may escape through an outlet 33. The openings in the ends 20 of the muffle through which the conveyor 27 extends are preferably provided with hinged sealing means 34 for preventing the escapement of hydrogen into the room in which the furnace is contained. 25 The temporarily secured together articles are subjected to a sufficiently high temperature to cause the copper or alloy containing copper to fuse with the ferrous metal of the parts, thereby forming alloy films containing copper and iron 30 at the junctions of the parts. These films are integrally united with substantially the entire area of adjacent surfaces of the parts in such a manner as to provide a welded joint therebetween. 35 Bearing caps of the type used in conjunction with connecting rods of the character disclosed may be formed by a similar process. As illustrated in Figs. 4 and 5, the bearing cap includes a ferrous metal collar 35 of semi-cylindrical shape which is provided at its extremities with rectangular shaped recesses 36 for receiving ferrous metal blocks 37. The surfaces of the recesses and blocks are covered with a coating containing copper and the blocks are preferably temporarily secured to the collar by pins 38 which extend through the 40 blocks and collar in the direction of the axis of the latter. When the parts are assembled in the relation shown in Figs. 4 and 5 the resulting assembly is placed upon the conveyor 27 and passed through the hydrogen furnace. 45 In the form of my invention illustrated in Figs. 50 6 and 7, the fabricated operative connecting device comprises a pair of spaced apertured ferrous metal disc or bearing portions 39 having grooves 40 in their peripheries. These discs are coated 55 with a copper containing alloy and connected together by a copper or copper alloy coated ferrous metal wire element 41 having its intermediate portion wrapped around the grooved portion of one disc throughout substantially more than 180° 60 thereof and its end portions are curved to conform with the curvature of the groove of the periphery of the other disc in which they are seated. The extremities of the wire element are preferably disposed in abutting relationship and 65 the intermediate portions of the wire element are somewhat crimped adjacent the inner sides of the disc so as to bring the sections of the wire element which are disposed between the discs into parallel relationship. A temporary clamping 70 member 42 is engaged upon the parallel sections of the wire 41 and releasably secured thereto by an adjustment screw 43 which urges these parallel sections together and firmly holds the device in an assembled relation while it is passing through the 75 hydrogen furnace. The heat to which the parts

of the device are subjected in the hydrogen furnace causes the copper containing coating on the contacting external surfaces of the parts to fuse or alloy with the ferrous metal of the wire and discs and thereby permanently and substantially integrally unite these parts together. 5

The structure of the parts of my improved fabricated articles, the manner in which they are assembled and the welding process employed assures fusion of only the adjacent surfaces of the 10 parts at a temperature substantially below that at which the ferrous metal parts lose their stability.

Although but several specific embodiments of the invention are herein shown and described, it will be understood that various changes in the 15 size, shape and arrangement of parts may be made without departing from the spirit of my invention or from the scope of the appended claims.

What I claim is:

1. A fabricated connecting rod including a ferrous metal journal portion having sockets therein, a pair of ferrous metal wire elements having adjacent ends received in said sockets and having longitudinally extending slots in their side 25 portions, the opposite end portions of said wire elements being offset outwardly with respect to each other, a bearing section comprising ferrous metal disposed between said outwardly offset end portions having sockets therein receiving parts of 30 the latter, a web comprising ferrous metal disposed between the intermediate portions of said wire elements having edges extending into the longitudinally extending slots thereof, and alloy 35 films containing copper and iron integrally united with the inner and outer registering surfaces of said sockets and wire elements respectively and between the adjacent surfaces of said web and longitudinally extending slots respectively.

2. A fabricated ferrous metal connecting rod 40 for operatively connecting together relatively movable elements of a mechanism, including spaced portions adapted to be drivingly and drivenly engaged, each having a pair of depressions and a recess formed therein, a pair of ferrous 45 metal wire elements having adjacent ends extending into said depressions, said elements having longitudinally extending slots in their side portions, a web structure comprising ferrous metal disposed between the intermediate portions of 50 said wire elements, said structure comprising a plate having edges extending into said slots and an angular flange extending into said recesses, and an alloy film containing copper and iron integrally united with substantially the entire area 55 of the respective registering surfaces of said wire elements, portions and web structure.

3. A fabricated ferrous metal connecting rod for operatively connecting together relatively 60 movable elements of a mechanism including spaced portions adapted to be drivingly and drivenly engaged and having depressions therein, a pair of ferrous metal wire elements having adjacent ends extending into said depressions, said 65 wire elements having longitudinally extending slots in their side portions, a web comprising ferrous metal disposed between the intermediate portions of said wire elements and having edges extending into said slots, and alloy films containing copper and iron integrally united with the juxtaposed surfaces of said wire elements and depressions and with said wire elements and said web.
